BAND TRACK

Robert W. Smith, Copley, Ohio, assignor to The
 B. F. Goodrich Company, New York, N. Y., a
 corporation of New York

Application October 22, 1947, Serial No. 142,078

Term of patent 14 years

(Cl. D90—20)

To all whom it may concern:

Be it known that I, Robert W. Smith, a citizen of the United States, residing at Copley, in the county of Summit and State of Ohio, have invented a new, original, and ornamental Design for a Band Track, of which the following is a specification, reference being had to the accompanying drawing, forming a part thereof.

Of the drawing:

Fig. 1 is a side elevational view of a band track, showing my new design.

Fig. 2 is an enlarged fragmentary plan view of the tread face thereof;

Fig. 3 is a side elevational view of the track shown in Fig. 2;

Fig. 4 is a cross-sectional view of the track taken on line 4—4 of Fig. 2; and

Fig. 5 is an enlarged fragmentary cross-sectional view taken on line 5—5 of Fig. 4.

I claim:

The ornamental design for a band track, as shown.

ROBERT W. SMITH.
